UNITED STATES PATENT OFFICE.

EDWARD R. IVES, OF BRIDGEPORT, CONNECTICUT, ASSIGNOR TO THE IVES,
BLAKESLEE & WILLIAMS COMPANY, OF NEW YORK, N. Y.

DESIGN FOR A TOY GUN.

SPECIFICATION forming part of Design No. 21,431, dated March 29, 1892.

Application filed February 8, 1892. Serial No. 420,791. Term of patent 7 years.

To all whom it may concern:

Be it known that I, EDWARD R. IVES, a citizen of the United States, residing at Bridgeport, in the county of Fairfield and State of Connecticut, have invented and produced a new and original Design for a Paper-Cap Toy Gun; and I do declare the following to be a full, clear, and exact description of the same, reference being had to the accompanying drawing, forming a part thereof.

The leading feature of my design consists in a toy gun of peculiar configuration and of surface ornamentation, as hereinafter described.

In the accompanying drawing, 1 denotes the barrel; 2, the stock proper; 3, the grip portion of the stock, and 4 the cap-seat. The stock proper 2 has on its surface panels 8, adapted to receive suitable inscriptions, and

between these panels scroll-work ornamentation 9. The grip portion 3 of the stock is in its outline extended below the stock proper and has its rear end rounded in outline, and the central portion of said grip portion has on its surface an ornamental panel 10, oblong in shape and irregular in form and containing a suitable ornamental figure. The cap-seat 4 is depressed below the upper outline of the barrel, the latter being of ordinary form.

I claim—

The design for a toy gun, substantially as shown and described.

In testimony whereof I affix my signature in presence of two witnesses.

EDWARD R. IVES.
